UNITED STATES PATENT OFFICE.

CHARLES M. COSNER, OF BLOOMINGTON, INDIANA.

FOLDING UMBRELLA.

1,294,055.

Specification of Letters Patent. Patented Feb. 11, 1919.

Application filed March 13, 1917. Serial No. 154,504.

To all whom it may concern:

Be it known that I, CHARLES M. COSNER, a citizen of the United States, residing at Bloomington, in the county of Monroe and

5 State of Indiana, have invented certain new and useful Improvements in Folding Umbrellas; and I do hereby declare the following to be a full, clear, and exact description of the invention, such as will enable others 10 skilled in the art to which it appertains to make and use the same.

This invention relates to improvements in folding umbrellas, and has for one of its objects the provision of a device of this 15 character which can be collapsed or folded so that it may be readily carried in a pocket, valise, or other comparatively small space.

A further object of this invention is the provision of telescopic ribs having means for 20 holding them extended, and which will permit telescoping of said ribs into folded position.

A still further object of this invention is the provision of a folding umbrella of this 25 character, which will be simple, durable and efficient, and which may be manufactured and sold at a comparatively low cost.

With these and other objects in view, the invention consists of the novel combination 30 and arrangement of parts, hereinafter more fully described and set forth in the claim hereto appended.

In the drawings:

Figure 1 is an elevation of my improved 35 umbrella assembled and in raised position,

Fig. 2 is a view showing the telescoping stick,

Fig. 3 is a view showing the umbrella assembled and in normally down position,

40 Fig. 4 is a view illustrating the umbrella in collapsed position,

Fig. 5 is a view illustrating the runner,

Fig. 6 is a view illustrating the top notch,

45 Fig. 7 is a view showing the locking member for the top notch.

Fig. 8 is a fragmentary longitudinal sectional view of the stick and its detachable handle, applied thereto,

50 Fig. 9 is a fragmentary sectional view of the top portion of the stick illustrating the top notch applied thereto,

Fig. 10 is an enlarged fragmentary sec-

tional view illustrating the manner in which the stick is held in extended position,

Fig. 11 is a detail fragmentary sectional 55 view of the lower end of the stick,

Fig. 12 is an enlarged fragmentary sectional view illustrating the notching member for holding the telescopic ribs in extended position.

60 Referring in detail to the drawings, the numeral 1 indicates a central section receiving in one end a section 2. The other end of the section 1 has a spring 3 secured 65 therein, and which extends exteriorly thereof and is provided with a head 3', adapted to be received by an opening 4' in a section 4 to lock the sections against movement with relation to each other. A flared portion 5 is formed on the free end of the section 4, and

70 has internal screw threads 6 for coöperation with screw threads on the handle 7, whereby the handle can be detached when desiring to substitute another therefor. The first-named

75 end of the section 1 is provided with an annular flange 5' for engagement with a collar 7', formed on the end of the section 2, to prevent the section 2 from being entirely withdrawn from the section 1. A catch 8, having a head 9, is secured in the section 2, 80 and the head thereof extends through an opening 10 into engagement with a flange 5' to prevent the section 2 from sliding inwardly of the section 1.

85 A top notch 11 is mounted on the section 2 and is limited against movement in one direction by a shoulder 10' and limited in the other direction by a plug 14, threaded in the section, as illustrated at 15. An annular flange 16 is formed on the plug and 90 has a wear point 17 arranged concentrically thereto. The top notch 11 includes a cylindrical sleeve 12 having a conical enlarged portion 13 intermediate its ends to which may be attached in the ordinary manner the 95 fabric of the umbrella.

100 Hollow ribs 19 are pivoted to the top notch, as shown at 20, and have longitudinally extending slots 21, which terminate short of the free ends thereof, as at 22, and the ribs at this point are offset to form spring members 23 in which are adapted to be seated enlargements 24 carried by solid ribs 25. The outer ends of the ribs 25 are adapted to

have the fabric of the umbrella secured thereto in the usual manner. By having the enlargements 24 in engagement with the spring members 23, the ribs 24 are held from sliding inwardly of the ribs 19, but when applying pressure on the ends of the ribs 25, the spring members 23 permit the enlargement to pass and enter the slots 21, whence the ribs 25 are free to slide inwardly by 5 the ribs 19. Extensions 26 are formed on the inner ends of the ribs 25 and have pivoted thereto staves 27, which extend through the slots 21 and are pivoted to a runner 28 10 slidable on the sections 1 and 2, as shown at 29. The runner 28 is provided with a slot to receive catches 18 carried and movable through slots 18' in the sections 1 and 2 15 for holding the ribs in a lowered or raised position.

20 To collapse the umbrella, the head 3' of the catch 3 is disengaged from the opening 4' in the section 4, and the section 1 is moved within said section and the catch 8 is disengaged from the opening 10, permitting the 25 section 2 to move within the section 1. The solid ribs 25 are then pressed, moving them inwardly within the hollow ribs 19, provid-

ing a compact device which can be readily and conveniently carried in a comparatively small space.

What is claimed is:

A folding umbrella comprising a telescopic stick, a top notch secured to said stick, a runner slidable on said stick, hollow ribs pivoted to the top notch and having slots terminating short of their free ends, offset portions forming spring members at the ends of the slots, solid ribs slidable in the hollow ribs, heads formed on the solid ribs and in engagement with the spring members to hold 35 said ribs extended, extensions formed on the inner ends of the solid ribs, and stays pivoted to said extensions and extending through the slots and pivoted to the runner, 40 said heads being received by the slots when 45 freed from the spring members upon collapsing the ribs.

In testimony whereof I affix my signature in presence of two witnesses.

CHARLES M. COSNER.
